UNITED STATES PATENT OFFICE.

DAN. L. ALLYN, OF BLOOMINGTON, ILLINOIS, ASSIGNOR OF ONE-HALF TO
CYRUS FRANK, OF SAME PLACE.

COMBINED CARPET AND WEATHER STRIP.

SPECIFICATION forming part of Letters Patent No. 364,462, dated June 7, 1887.

Application filed February 2, 1887. Serial No. 226,276. (No model.)

To all whom it may concern:

Be it known that I, DAN. L. ALLYN, of Bloomington, in the county of McLean and State of Illinois, have invented a new and Improved Combined Carpet and Weather Strip, of which the following is a full, clear, and exact description.

My invention has for its object to provide a combined carpet and weather strip adapted to be placed beneath a door, which, when the door is open, will present the appearance and serve the purpose of the usual carpet-strip, and when the door is shut will be operated automatically thereby to tightly close the bottom seam against the admission of cold air.

The invention consists in the construction and combination of parts, as hereinafter clearly described, and particularly pointed out in the claim.

Reference is to be had to the accompanying drawings, forming a part of this specification, in which similar letters of reference indicate corresponding parts in all the figures.

Figure 1 is a transverse sectional view of my improved combination carpet and weather strip, on the line $x-x$, Fig. 2, the doorway to which it is applied being in elevation and the door open. Fig. 2 is a plan view of the strip, the door and posts being in section. Fig. 3 is an inverted plan view of one end of the combination strip.

The combined carpet and weather strip is composed of two longitudinal sections, A B, of equal height, and beveled or rounded on the outer edges, so that when united and fitted between the door-posts, as shown in Fig. 2, a strip is formed having a flush surface, and serving the usual purpose of a border to the edge of the carpet C.

The inner section, A, is stationary, and is fixed in the space beneath the closed door by screws D. The sections A B are chambered longitudinally on their under sides, and from the interior of section A project hook-lugs E into the interior of section B, where they are

engaged by lugs F, projecting downward from the inner edge of the same.

The hook-lugs E retain the section B in place, and the adjacent edges of the lugs E F are beveled or inclined, for a purpose to be presently described.

On the end of the section B adjacent to the hinged edge of the door is formed an upwardly-projecting lug, G, which, when the door is closed, is struck, as by a cam, by the inner lower end of the same, or by a wear-plate, H, thereon, thereby causing the inclined faces of the lugs F to ride up the inclined faces of the lugs E, as the inner inclined edge of the section B is raised, the outer edge resting on the floor, as shown in Fig. 1.

A molding, K, is secured across the lower outer side of the door, is cut away at L to permit the engagement of the lug G with the same, and is undercut at M at its lower edge, to receive and form a tight joint with the inner edge of section B when the same is raised by the door.

The outer section, B, is rendered detachable by its hooks and lug connection with section A, so that it can be easily removed for cleaning purposes.

Having thus described my invention, what I claim as new, and desire to secure by Letters Patent, is—

As an improved article of manufacture, a combined carpet and weather strip comprising the section A, having the forwardly-projecting hooked lugs E extending beyond its inner edge and beveled on their inner faces, and the section B, recessed in its under surface to receive the lugs E, and provided with downward-projecting beveled lugs F, engaging the beveled lugs E, and with the upward projection G at one corner of its inner inclined edge, substantially as set forth.

DAN. L. ALLYN.
